UNITED STATES PATENT OFFICE.

THOMAS B. RYAN, OF NEW BEDFORD, MASSACHUSETTS.

SAFETY-POCKET.

1,089,270.

Specification of Letters Patent. Patented Mar. 3, 1914.

Application filed August 25, 1911. Serial No. 645,941.

To all whom it may concern:

Be it known that I, THOMAS B. RYAN, a citizen of the United States, and resident of New Bedford, county of Bristol, State of 5 Massachusetts, have invented certain new and useful Improvements in Safety-Pockets, of which the following is a specification.

This invention relates to a safety pocket for the garment of a carpenter or other 10 mechanic, and its object is to provide a simple, practical, and inexpensive pocket adapted to receive a folded rule and prevent the same from falling out or being surreptitiously removed.

15 The novel features of the invention will be apparent from the following description taken in connection with the accompanying drawings.

In the drawings, Figure 1 is a perspective 20 view of a portion of a garment, having my invention thereon; Fig. 2 is a view similar to Fig. 1 and showing a rule in position to be introduced into the pocket or withdrawn therefrom; and Fig. 3 is a longitudinal sectional view through the middle of the pocket with a rule therein.

The pocket may be placed either on the outside or inside of the garment and in the particular form illustrated, I have shown it 30 as employed on the side of the leg of a pair of "overalls" designated by the numeral 1. The pocket 2 on the garment is fastened thereto, along the sides and bottom by stitching 3 and has an open top. A transverse opening 4 in the pocket extends across substantially the greater portion of the width of the pocket, preferably near its top, and is of such size and shape as to enable one of the folds of a rule to be conveniently passed 40 therethrough in introducing the same into the pocket or in withdrawing it therefrom. The opening 4 leaves a strip or guard 5 at the top of the pocket and when the rule is in the pocket this guard lies between the 45 folds of the rule and serves as a retaining means to prevent it from being accidentally displaced or surreptitiously removed. The pocket, which is relatively long and narrow,

is of such length that the rule will protrude some distance above the top so that it may 50 be conveniently grasped when it is desired to remove it from the pocket.

In introducing the rule into the pocket it is placed flat against the latter, with its hinge downward and the folds slightly 55 open, and then drawn upwardly, so that one fold passes through the opening 4 and behind guard 5, until hinge 7 reaches guard 5, the position shown in Fig. 2. The rule may then be readily dropped into the pocket, assuming the position illustrated in Fig. 1. In order to withdraw the rule from the pocket it is first drawn upwardly to the position shown in Fig. 2 and then moved away 60 from the garment slightly and passed downwardly outside of the pocket until free from guard 5.

It is evident that in case of any tendency for the rule to fall out of the pocket as for example when the latter is, for any reason inverted, the guard 5 will engage hinge 7, and thus prevent the rule from leaving 70 the pocket. By providing the opening 4 in the pocket itself and thereby having the guard integral therewith, a very simple and 75 inexpensive safety pocket is produced which is not unsightly and is of great practical value.

Having thus described the invention, what is claimed is:

A garment pocket for sectional rules, comprising a section of the garment, and an outer wall connected to said garment to form an elongated pocket, said outer wall consisting of a single strip of material provided 85 near the top free margin with a horizontal elongated opening adapted to receive and have passed therethrough a section of said rule, whereby said rule is prevented from accidentally dropping from said pocket. 90

In testimony whereof I affix my signature in presence of two witnesses.

THOMAS B. RYAN.
